CLAIM

The ornamental design for a acupressure device, as shown.

DESCRIPTION

FIG. 1 is a front perspective view of a acupressure device showing my new design;

FIG. 2 is a front elevational view thereof, the rear view being a mirror image thereof;

FIG. 3 is a left side elevational view thereof, the right side being a mirror image thereof;

FIG. 4 is a top plan view thereof; and,

FIG. 5 is a bottom plan view thereof.
